UNITED STATES PATENT OFFICE.

ALFRED H. LORTON, OF NEW YORK, N. Y.

SCUTTLE.

SPECIFICATION forming part of Letters Patent No. 340,722, dated April 27, 1886.

Application filed September 5, 1885. Serial No. 176,249. (No model.)

To all whom it may concern:

Be it known that I, ALFRED H. LORTON, of the city and county of New York, in the State of New York, have invented a certain new and useful Improvement relating to Scuttles, 5 of which the following is a specification.

The invention is adapted to serve in dwelling-houses, hotels, manufactories, and in roofs generally. It is superior to the ordinary 10 scuttles in the matter of safety from fire, security of fastening, and facility of operation. The scuttle is circular. I spin or stamp a metal coaming, with provisions to facilitate tight junction of a metallic roofing therewith, 15 and with provisions for accommodating a fastening-ring. I provide a ring just within the coaming, and capable of turning loosely, with provisions for engaging and liberating the scuttle-cover by a turning motion. I spin or 20 stamp a cover of metal adapted to match tightly over the coaming, and I provide a quick screw with provisions for partially turning it from below, which effects the double function of lifting the scuttle-cover and turning 25 it on the screw-shaft as an axis, so as to easily open or close the scuttle by a partial revolution in one direction or the other.

The accompanying drawings form a part of this specification, and represent what I consider 30 the best means of carrying out the invention.

Figure 1 is a central vertical section. The strong lines show the scuttle closed; the dotted lines show the position of the cover when the 35 scuttle is open. Fig. 2 is a corresponding plan view. The succeeding figures represent portions on a larger scale. Fig. 3 is a vertical section. Fig. 4 is a horizontal section on the line xx in Fig. 3. Fig. 5 is a vertical section, and 40 Fig. 6 a corresponding elevation, showing the inner face. Fig. 7 is a vertical section, and Fig. 8 a corresponding elevation, showing the inner face.

Similar letters of reference indicate corresponding parts in all the figures where they occur.

A is the roof, a a circular hole therein, and B an ordinary covering of tin plates; or, technically, "terne plates," soldered together. 50 D is the coaming, of sufficiently stout sheet-iron, steel, or other metal, certain portions be-

ing designated, where necessary, by additional marks, as D' D'' . This coaming is spun up or otherwise produced with a broad flange, D' , lying directly on the roof A. At the inner 55 edge of this flange D' is a short vertical cylinder or truncated cone constituting a riser, D'' , extending upward to a sufficient height to defend against water on the roof. The metal extends inward from the top of D'' , as indicated by D^3 . It extends downward from the inner edge of D^3 a little distance, as indicated by D^4 .

D^* is an annular recess, spun or otherwise produced in the flange D' . 65

In setting the coaming the adjacent edges of the metal covering B are sheared or otherwise trimmed to the right form and bent sharply downward into this recess. A tight joint is then made by solder C. I prefer to 70 apply enough solder to completely fill the narrow recess D^* .

In the top D^3 are slots d , forming an equally-spaced series extending around the coaming. Threestout projections, D^5 , are riveted or otherwise 75 permanently attached on the inner face of D^3 .

E is a ring of iron or steel having vertical grooves e on its exterior corresponding to the projections D^5 . The ring is forced up into 80 place, while these grooves correspond with the projections D^5 . When it is up it is partially turned, and is supported on the projections. Its upper edge carries hooks E' . A lever, F, turning on a fixed center, f , engages a lug, E^2 , 85 on the ring E, and serves as a convenient means for turning the ring to a sufficient extent in one direction or the other.

M is the scuttle-cover, certain portions being designated, when necessary, by additional 90 marks, as M' . It is stamped or otherwise produced in the dome-shaped form represented. This cover matches over the coaming. The hanging lip M' at its periphery fits tightly against the portion D^2 , resting when down by 95 the extreme edge of M' matching on an offset in D^2 , or by an offset on the interior of the cover M matching on the top D^3 of the coaming. The interior of the cover is braced by cross-ribs M^2 . The center is equipped with 100 holes m , which allow ventilation through apertures in a cylindrical riser, M^3 , which are

shielded from weather by an overhanging lip, M⁴. The center of the top is closed by a stout glass plate, M⁵. Light enters through the glass M⁶, and the apertures m. The cover is 5 spun or otherwise produced with circular corrugations M⁶ as shown, which contribute, with the cross-ribs M⁷, to give more strength with lightness.

The invention may serve usefully by lifting 10 off and on in the obvious manner by hand; but I have provided means for operating from below with great facility. A bracket, A', bolted or otherwise firmly fixed to the roof A, supports, by means of a collar, G', a hollow 15 shaft, G, which extends downward to any desired distance, and is equipped with a turning handle, G². The interior of G is equipped with six screw-threads, g, having a quick pitch. These engage with corresponding screw- 20 threads, h, on an inclosed vertical shaft, H, which latter is adjustably set in the socket M', brazed or firmly fixed in the interior of the scuttle - cover M, being confined by a pinching - screw, m⁷. A collar, H', on the 25 shaft H engages under the part D⁴ of the coaming and prevents the cover from being lifted too high under any circumstances. The bracket A' and its connections are set close to one side of the interior of the scuttle, 30 so that they shall interfere but little with the use of the scuttle when the cover is off.

J is a fixed post, serving as a stop for the scuttle-cover in its turning movement. It is so placed and is of such thickness that one 35 post serves to stop the swinging motion in each direction—that is to say, when the cover isswung into the position to close, it strikes the stop J, which thus forbids its turning any further on the shaft H as an axis, and compels it 40 to sink vertically. When the opening motion is completed, the cover swings around until it again strikes the stop J, this time striking it on the nearly-opposite face to that which was before effective. There are brazed or otherwise 45 strongly set in the interior of the cover M hooks M⁸, coinciding in number and position with the slots d. When the cover M is in the correct position and is lowered so that its lip M' matches over the exterior of D², the hooks 50 M⁸ sink into the slots d. These hooks stand so related to the hooks E' that the partial turning of the ring E in one direction or the other by operating the lever F engages or disengages the hooks M⁸, thereby locking or un-locking the scuttle-cover.

Operation: Assuming the scuttle to be closed and the cover fastened, the operator, wishing to open it, first turns the lever F, and thereby shifts the locking-ring E so as to disengage the 60 hooks E' from the hooks M⁸. Next he grasps the handle G² and applies his strength to turn the hollow shaft G. This, through its screw-threads g, tends to lift and to turn the inclosed screw-threaded shaft H, rigidly attached to the 65 scuttle-cover M. As the engagement of the lip M' over the coaming forbids the latter to turn, the action of the screw causes it to rise

directly upward. This motion continues until the cover is completely above the coaming, then the turning force of the hand imparts a 70 direct turning motion to the cover. The cover M no longer rises, but turns freely around on the shaft H as the axis. This motion is continued until the cover is turned into the position which opens nearly the whole area of the 75 scuttle. It may remain in this position for any length of time. When it is desired to close the scuttle, the operator takes hold of the handle G² and imparts the required turning force. The first effect is to swing the entire 80 cover around until it strikes the stop J; then the turning force, acting through the screw-threads g, aided by the gravity of the cover, causes it to sink with a direct vertical motion until its lip M' is again tightly matched upon 85 the exterior of the coaming. In this movement the hooks M⁸ have again sunk into the slots d. Now, a movement of the lever F turns the ring E and engages the hooks E' 90 with the hooks M⁸, and the scuttle is secured.

The ordinary scuttles and scuttle-covers are difficult to make tight, and are specially dangerous in case of fire in an adjoining building which throws flames across the roof. My scuttle-cover and coaming are all of incom- 95 bustible material.

Ordinary scuttle-covers are frequently secured by means which are difficult to operate, and are useless until considerable delay has been experienced in removing the fastenings. 100 My scuttle requires simply the operating of the lever F and the turning of the handle G². The pinching-screw m⁷ allows the cover M to be shifted up and down relatively to the screw H and to the collar H', which limits the vertical motion. I attach importance to the fact that the coaming and also the scuttle-cover and hatch are entirely of fire-proof material. 105

Modifications may be made in many of the details. Parts of the invention can be used without the whole. I can dispense with the locking-hooks E' and the means for operating them and secure the cover by other means. I can dispense with the pinching-screw m⁷, and secure the shaft H unchangeably to the scuttle. 110 I can dispense with the ventilating-apertures. I can dispense with the glass, making the whole top opaque. I can dispense with the collar H', depending on the gravity of the cover to limit the vertical movement, and insure a 115 prompt lateral movement so soon as the cover has been sufficiently lifted. I prefer the whole, as shown.

I claim as my invention—

1. The scuttle-cover M, adapted to turn on 125 a shaft out of the center, in combination with means for raising and turning it by power applied to said shaft from below, substantially as herein specified.

2. The screw-threaded shaft H h, with its 130 collar H', in combination with the correspondingly screw-threaded hollow shaft G g, and with a scuttle-cover and a coaming having an internal part, D⁴, arranged to match the col-

lar H', arranged for joint operation, as herein specified.

3. In combination with a scuttle-cover, M, capable of both a vertical and a turning motion, the stop J, arranged to arrest the motion when it is turned to the proper extent in either direction, as herein specified.

4. In a scuttle, the locking-ring E, having hooks E', in combination with a coaming, D, and means D⁵ for supporting said ring, and with a hatch-cover, M, having hooks M³, arranged for joint operation, as herein specified.

5. The coaming D, having a soldering-recess,

D*, in combination with the roof A, having an aperture, a, and with the metal covering B 15 and solder C, and with a suitable scuttle-cover, M, and means for operating it, all combined and arranged to serve substantially as herein specified.

In testimony whereof I have hereunto set 20 my hand at New York city, New York, in the presence of two subscribing witnesses.

ALFRED H. LORTON.
